UNITED STATES PATENT OFFICE.

JOHN A. LIEB, OF NEW YORK, N. Y., ASSIGNOR TO AMERICAN TELEGRAPHONE COMPANY,
A CORPORATION OF THE DISTRICT OF COLUMBIA.

MAGNET FOR TELEGRAPHONES.

No. 889,317.

Specification of Letters Patent.

Patented June 2, 1908.

Application filed March 25, 1907. Serial No. 364,510.

To all whom it may concern:

Be it known that I, JOHN A. LIEB, a citizen of the United States, residing at the city of New York, in the borough of Brooklyn and State of New York, have invented certain new and useful Improvements in Magnets for Telegraphones, of which the following is a full, clear, and exact description.

My invention relates to certain features of improvement in electromagnets and particularly in the recording and reproducing electromagnet of an apparatus for magnetically recording sound and speech. A well known example of a machine of this type is the telephone, to which my present invention is applicable.

In the telephone and similar apparatus, a steel disk, wire or plate is continuously moved in close proximity to the pole or poles of an electromagnet which is in a telephone circuit. The sound undulations of the telephone circuit are magnetically recorded on the steel by the changing magnetism of the electromagnet. It is necessary to have the plate moved in quite close proximity to, or in actual contact with, the pole piece to secure the best results, and it is evident that the pole piece is liable to be worn away by the friction unless special means are provided for avoiding this.

By the present invention I arrange to form the pole piece with a protecting armor or shield which receives substantially all the wear of the frictional contact, but which does not in any way interfere with the magnetic and electrical functions of the mechanism. For this purpose I prefer to employ a hollow protecting cylinder of hard or wear resistive metal or material which surrounds the pole piece at the point of contact with the steel recording and reproducing medium.

The invention further consists in the features of construction and combination hereinafter set forth and claimed.

In the drawings: Figure 1 is a side view of the electromagnet and a recording and reproducing medium in substantially the relations they occupy in use; the construction of the pole piece of the electromagnet embodies the principles of my invention; Fig. 2 is a detail view of the magnet core and its protecting armor; Fig. 3 is a similar view showing a slight modification; Fig. 4 shows a still further slightly modified construction; and Fig. 5 is a form of the invention adapted for

use with steel wire as the recording and reproducing medium.

Referring to the drawings in which like parts are designated by the same reference sign, 1 indicates a disk or plate of hardened steel which constitutes the recording and reproducing medium of the device.

2 is an electromagnet having a core 3, and a polar extension 4, which is of reduced diameter so as to concentrate the lines of force of the electromagnet into a very limited area of action on the steel medium 1.

5 denotes a protecting hollow cylinder of anti-friction or wear resistive metal or material, such as brass or a watch jewel. The central opening 6 of this protecting cylinder is of just sufficient size to tightly fit the polar extension 4, and when so placed the end surface of the cylinder and that of the pole 4 are flush.

In use the medium 1 rotates or moves past the electromagnet 2, and the wear is for the most part received by the larger surface of the anti-friction cylinder 5. In this way rapid wear on the pole piece is prevented and it retains its original and proper form and condition.

In Fig. 3 a slightly modified construction is shown which insures a better contact between the pole piece and the medium 1, in spite of inequalities or foreign substances on the surface of said medium, since it does not present such a wide base or area to rest on the moving plate. It will be noted that the cylinder 5 has two lateral faces 7 formed by beveling or cutting away, so that the face 8 of the armor or protecting device is not substantially wider than the diameter of the polar extension 4. The length of the face 8 is, however, sufficient to provide adequate area for resisting the wear. The long dimension of the face 8 should preferably be in the direction of movement of the medium 1.

A further feature of the construction in Fig. 3 is that an additional polar extension 4' is provided on the other end of the core 3, so that when one end becomes worn the core may be reversed to utilize the other. This may be equipped with a protecting or armor device 5, exactly similar to that at the other end of the magnet. The two protecting devices are assembled with their elongated faces 8 extending in the same direction. In this way by observing the upper end it can be seen when the lower face is adjusted in line.

with the direction of movement of the steel medium.

In Fig. 4 the protecting piece 9 is of conical form, with a central hole or opening 10, to fit 5 upon the polar extension 4. This construction gives a narrow zone or ring 11, immediately around the edge of the pole to serve as an anti-friction or wear resistive surface.

In Fig. 5 a form of the invention is shown 10 which is adapted for use with steel wire as a record receiving medium. The protecting piece is generally similar to the forms of Figs. 2 and 3, having a cylindrical body 5, and as shown a single bevel face 7, and a central hole 6. There is, however, a groove 12 diametrically cut or formed across the face of the protecting piece, and which serves as a guide for the wire. In this way the wire is constrained to move in proper relation to the 15 polar extension 4, and the heel of the cylinder taking the wear. The device 5, however, need not be beveled at all.

What I claim, is:—

1. In combination with the recording and 25 reproducing medium of a telephone, an electromagnet having a pole piece adapted for contact with said medium continuously traveling tangentially past its face, said pole piece being provided with a wear resistive 30 device.

2. In combination with the recording and reproducing medium of a telephone, an electromagnet having a pole piece adapted for contact with said medium continuously 35 traveling tangentially past its face, said pole piece having a wear resistive collar surrounding its extremity and flush with the end thereof.

3. In combination with the recording and 40 reproducing medium of a telephone, an electromagnet having a pole piece with a reduced polar extension, said extension being provided with a wear resistive device.

4. In combination with the recording and 45 reproducing medium of a telephone, an electromagnet having a pole piece adapted for contact with said medium continuously traveling tangentially past its face, said pole piece having a wear resistive device having a 50 contact surface flush with the end surface thereof.

5. In combination with the recording and reproducing medium of a telephone, an electromagnet having a pole piece adapted 55 for contact with said medium continuously traveling tangentially past its face, said pole piece having a wear resistive device fixed thereto and flush with the end surface thereof.

6. In combination with the recording and 60 reproducing medium of a telephone, an electromagnet having a reduced polar extension adapted for contact with said medium

continuously traveling tangentially past its face, and a wear resistive device surrounding said polar extension.

7. In combination with the recording and reproducing medium of a telephone, an electromagnet comprising a core having a protecting hollow cylinder constituting a wear resistive device and surrounding the 70 pole of said electromagnet.

8. An electromagnet for instruments for magnetically recording and reproducing sound, comprising a core having a hollow wear resistive device surrounding its pole, 75 two sides of said device being beveled or cut away reducing the width of the device to substantially the diameter of the pole.

9. An electromagnet for instruments for magnetically recording and reproducing 80 sound, comprising a core having two polar extensions and wear resistive devices surrounding each of said polar extensions, their end faces being flush with the ends of said extension.

10. An electromagnet for instruments for magnetically recording and reproducing sound, comprising a core having a wear resistive device on one pole thereof, said resistive device being elongated on its wearing 90 surface.

11. An electromagnet for instruments for magnetically recording and reproducing sound, comprising a core having a wear resistive device on one pole thereof, said resistive device being elongated on its wearing 95 surface, and an indicator on the other end of said core by which said device is properly positioned.

12. An electromagnet for instruments for 100 magnetically recording and reproducing sound, comprising a core having a wear resistive device surrounding each of its poles, the end faces of said resistive device surrounding each of its poles, the end faces of 105 said resistive devices being flush with the ends of the pole, and each of said devices being elongated on its wearing surface in the same direction, whereby one pole may be properly positioned for use by observing the 110 other as an indicator.

13. In combination with the recording and reproducing medium of a telephone, an electromagnet having a pole coöperating 115 with said medium, and a jewel associated with said pole, and constituting a wear-resistive device.

In witness whereof, I subscribe my signature, in the presence of two witnesses.

JOHN A. LIEB.
